UNITED STATES PATENT OFFICE.

ERNEST C. JOHNSON, OF MICHIGAN CITY, INDIANA, ASSIGNOR TO JAMES A. THORNTON, OF SAME PLACE.

FOLDING SCREEN FOR BEDS.

SPECIFICATION forming part of Letters Patent No. 244,613, dated July 19, 1881.

Application filed September 4, 1880. (No model.)

To all whom it may concern:

Be it known that I, ERNEST C. JOHNSON, a citizen of the United States, residing at Michigan City, in the county of La Porte and State of Indiana, have invented certain new and useful Improvements in Folding Screens for Beds, which are fully described in the following specification, reference being had to the accompanying drawings, in which—

10 Figure 1 represents a plan view of a folding screen-support containing my improvements; Fig. 2, a vertical section taken on the line *x x*, Fig. 1; Fig. 3, a side elevation of the same folded up, and Figs. 4 and 5 plan views, showing slight modifications in the construction of the support.

My invention relates to a support for screens for beds and other articles of furniture, the object being to provide a screen and support which can be readily folded up out of the way.

20 The invention consists in a double-jointed support projecting over the bed or other piece of furniture, and provided with cords by means of which it is folded up on both these joints and unfolded at will.

25 It also consists in other combinations of specific devices, all of which will be hereinafter fully described, and the special improvements which it is desired to secure by Letters Patent 30 pointed out definitely in the claims.

35 In the drawings, A represents a post of any suitable length and size, according to the size of the frame and weight of the screen which is to be used. On one side of this post a short arm, *a*, projects. A skeleton-frame, B, composed of two central bars, *b*, separated slightly, and two cross-arms, *b'*, passing through the ends of the former, to which they are fastened, is pivoted to the projecting arm *a* by arranging it between the ends of the middle bars and passing one of the cross-bars through it and said middle bars, as shown in Fig. 1 of the drawings. At the other end of the frame a second frame, C, is hinged, consisting of a central bar, *c*, the inner end of which is embraced by the middle bars, *b*, to which it is connected by the front cross-arm, *b'*, on which it turns as a pivot. At the front end of this bar *c* is a cross-bar, *c'*, like those on the first frame. The rear 45 end of the bar *c* projects slightly behind its

55 pivot, and is provided with a stop, D, which strikes against the under side of the bars *b* when the frame C is lowered to a horizontal position. A stop, E, is attached to the arm *a*, projecting on each side of the latter to the rear extensions of the arms *b*, which strike against these projections of the stop and stop the frame B when it is lowered to a horizontal position. Two cords are attached to the rear end of the arm *c*. One of them, F, is extended forward 60 underneath the arm, around its forward end, and up through a ring, *f*, on the top of the post A. The other cord, G, is carried back underneath the frame B and passes down through an eye, *g*, attached to the post A, just 65 underneath the arm *a*.

Cords H may be arranged on the sides of the support connecting the outer ends of the cross-bars, the post of which support is fastened to the back of the head-board I when it 70 is used for a bed-screen, and when used to cover or protect any other article of furniture it must be fastened to some suitable support. The support makes a kind of square frame, 75 over which the screen is thrown, and to which it is attached, whatever the material.

Suppose the support lowered in a horizontal position, as shown in Fig. 2 of the drawings, a pull on the end of the rope F will first fold the front frame, C, up and back upon the frame B, by reason of the attachment and arrangement of the cord. A continuation of the pull will then fold the frame B up against the post, carrying with it the frame C, the arms assuming the position shown in Fig. 3 of the drawings. Obviously the screen will thus be folded up and back out of the way. Now, when it is desired to lower the screen a pull on the cord G will first fold the frame B down into a horizontal position, and a continuation of the pull will then fold the frame C outward into a horizontal position, owing to the attachment and arrangement of the cord G.

It will be seen, therefore, from the above description that with this folding support bed-screens may be folded back out of the way with ease, and folded down over the bed at pleasure, when required. The double folding brings the screen into such a position that it will cover the frames to a considerable extent, 100

and present even an ornamental appearance, something like a lambrequin. This frame is especially adapted for use with mosquito-bars, but, of course, may be used with screens of other material, if desired, and may be applied elsewhere than over beds.

Some modifications may be made in the constructions of the frames. Instead of the double bars b a single bar, b , may be employed, as shown in Fig. 4 of the drawings, and side bars, b^2 and c^2 , may be employed, as shown in the same figure, in which case, of course, the side cords will be dispensed with. This construction will make a somewhat stiffer frame, and with it the central bars may be dispensed with, as shown in Fig. 5 of the drawings, in which figure the frame B is also shown hinged or pivoted to two supporting-posts, one at each corner, instead of one central one. A single central bar may, however, be employed with the style of frames shown in Fig. 5, as well as two, in fact is preferred. With two supporting-posts at the corners it is necessary to have two sets of cords, in order to work the support readily.

The construction and arrangement of the stops may be modified to suit different styles of frames and convenience.

If it is desired to fold up the support still more compactly, it may be made in three sections, instead of two, the third being a duplicate of the second.

Washers J may be applied to the pivot-pins on each side of the jointed bars, if desired, and the bars may be held in position where single ones are used by pins passing through the pivot bars, or any other suitable devices.

The construction of the hinge-joint may also be varied. For instance, a regular butt-hinge may be used for connecting the several parts together, the connecting-arms in such cases being arranged in line with each other.

I do not limit myself to the precise construction and arrangement of parts herein shown and described.

Having thus described my invention, what I

claim, and desire to secure by Letters Patent, is—

1. A double-jointed screen-support for beds and other articles of furniture, composed of a frame-work, B, hinged to a suitable support, and provided with a stop at the supported end, whereby it is prevented from falling below a horizontal position, and a frame-work, C, hinged to the front end of the former frame, and provided with a stop at the hinged end, whereby it is prevented from falling below a horizontal position, substantially as and for the purpose set forth.

2. A frame, B, hinged to a suitable support, and provided with a stop at the supported end, whereby it is prevented from falling below a horizontal position, in combination with a frame, C, hinged to the front end of the former frame, and provided with a stop at the hinged end, whereby it is prevented from falling below a horizontal position, and a cord, F, attached to the hinged end of the frame C, whereby the hinged support may be successively doubled upon itself in a horizontal position and folded up, substantially as described.

3. The hinged frame B, in combination with the frame C jointed thereto, and the cord G, arranged as described, whereby the folded frame may be turned down and unfolded, substantially as described.

4. The supporting post or posts A, in combination with the double-hinged screen-support B C and the cords F and G, arranged as described, whereby the support may be folded and unfolded on its two hinges, substantially as described.

5. The supporting-post A, in combination with the double-hinged screen-support B C, provided with transverse arms b' , stops D and E, and raising and lowering cords F and G, all constructed, arranged, and operating substantially as described.

ERNEST C. JOHNSON.
